Primary Examiner — Garth Rademaker*Assistant Examiner* — Melanie Pellegrini(74) Attorney, Agent, or Firm — Egbert Law Offices, PLLC(57) CLAIM

The ornamental design for a pendant set, as shown and described.

DESCRIPTION

FIG. 1 is a perspective view of a pendant set showing our new design.

FIG. 2 is a front view thereof;

FIG. 3 is a rear view thereof;

FIG. 4 is a side view thereof;

FIG. 5 is an opposite view thereof;

FIG. 6 is a top view thereof; and,

FIG. 7 is a bottom view thereof.

The broken lines in the drawings represent unclaimed portions of the pendant set and form no part of the claimed design.
